UNITED STATES PATENT OFFICE.

JOHN STROTHER MILLER, JR., OF RAHWAY, NEW JERSEY, ASSIGNOR TO THE BARBER
ASPHALT PAVING COMPANY, OF PHILADELPHIA, PENNSYLVANIA, A CORPOR-
ATION OF WEST VIRGINIA.

FLOOR-COVERING.

1,360,663.

Specification of Letters Patent. Patented Nov. 30, 1920.

Application filed July 10, 1919. Serial No. 309,896.

To all whom it may concern:

Be it known that I, JOHN STROTHER MILLER, Jr., a citizen of the United States, residing at Rahway, in the county of Union 5 and State of New Jersey, have invented certain new and useful Improvements in Floor-Coverings, whereof the following is a specification.

My invention relates to floor covering and 10 the like of the oilcloth or linoleum type, and especially to the "base" or fabric which carries the "overlay" material or composition that forms the wearing surface, and to the relation of the overlay to the base. It is 15 my aim to improve the quality of the product, and especially to prevent the occurrence of certain annoying defects which sometimes mar its appearance and impair its salable value. The view shown in the drawings is a 20 section of the product claimed.

The type of sheet material to which I refer is very commonly composed of a "base" 25 layer of rag felt saturated or impregnated with liquid pitch, such as natural asphalt (suitably purified and fluxed, if necessary) or coal tar pitch. The "overlay" comprises, 30 generally speaking, an application or coat of primer containing pigment, a coat of ground color of paint or of linoleum composition, and a design in suitably colored linoleum 35 composition or paint printed upon the ground color. In the case of so-called "inlaid" linoleum, the ground color and the imprinted design are replaced by an inlaid linoleum mixture.

The base layer of felt is saturated or impregnated to such a degree as to be black throughout. Owing to high, hard spots in 40 the surface of the raw felt due to incomplete disintegration of the felt material, the saturated or impregnated felt is liable to present bright spots, such as are called "high hats". Other bright spots may be produced by excessive saturation,—especially in places 45 where low places in the raw felt allows the formation of a surface coat or deposit of the impregnating material. Bright spots of either sort tend to give rise to imperfections when the primer coat is applied, because the 50 knife edge, under which the primer is usually applied, scrapes it off at such places. The result is that the pitchy saturation is permitted to come in direct contact with the ground color when the latter is subsequently 55 applied, with the result that the saturation

generally strikes through the ground color and produces discoloration in the visible surface of the finished sheet linoleum.

In accordance with my invention, I overcome these difficulties by plying to the saturated or impregnated felt layer an unsaturated surface layer of fabric, such as cloth or other textile fabric, or paper,—preferably a sheet of kraft paper,—so that the base of the linoleum sheet is no longer made 60 up of the felt layer alone, but of the felt and fabric fastened or plied together. The paper may, if preferred, be sized so as to be non-absorbent. The fabric may be thus plied to the saturated felt by means of asphalt or other pitch more or less similar to that with which the felt is saturated,—employed by way of a cement or adhesive. To illustrate, one method of procedure is to pass rag felt such as is familiar to all versed in 65 the art through a saturating bath of hot bituminous material, squeeze out the excess, coat one face with a hot, molten, bituminous substance as the adhesive, and immediately apply the paper or textile fabric to the coated 70 face. The product is then cooled and either rolled up or can, after cooling, pass directly to the linoleum machines, where the oil overlay (whether paint or true linoleum 75 composition) is applied.

Ordinarily speaking, it will be unnecessary—and, especially in the case of paper, even undesirable—to apply the fabric to both sides of the felt layer, since both the "stock" 80 during manufacture and the sheet linoleum 85 when finished are commonly handled, stowed, and shipped in rolls, and since if plied paper and felt be rolled with the paper on the inside, there will be serious buckling of the paper when the stock or the finished linoleum is subsequently laid out flat again. Since, however, the fabric is primarily intended merely to form the overlay-receiving 90 surface of the base, and since linoleum is customarily rolled with the overlay side out, a 95 base plied with paper on just one side offers no practical disadvantages or difficulties unless it be rolled too small,—as on a core of less than about six inches diameter.

The use of the composite base which I 100 have just described not only offers the advantage that bright or rough spots in the saturated felt no longer give rise to defects such as described above, but involves distinct and positive advantages. In the first 110

place, the black color of the saturated felt is objectionable, and with the old type of base it was, therefore, necessary to employ a primer containing pigment, in order that the 5 black might be completely masked. With my base, however, it is possible, by suitable selection of the color of the fabric used, to employ a better and less expensive transparent primer (*e. g.*, shellac), and even, in some 10 cases, to dispense with the ground color coat altogether, so that application of the transparent primer may be the only treatment of the base to prepare it properly for the imprinting of the desired design with suitably 15 colored paint or linoleum composition or for application of the inlaid linoleum mixture. The fabric (especially kraft paper), moreover, takes the priming, the ground coat, and the "top finish" of imprinted paint 20 or linoleum composition or of inlaid linoleum mixture all as well or better than the saturated felt. The transparent primer tends to develop the color of the paper,— 25 though in some cases it may be dispensed with entirely, if the design is such as to cover the paper completely.

The reverse side of the linoleum sheet may either be left unfinished, or may be finished 30 with a coat of paint or in any other usual or preferred way. It is advantageous to 35 ply to the reverse side of the base a backing of such textile fabric as jute or paper burlap (also by means of asphalt or other pitch as a cement) to afford greater strength: this is, of course, done about the same time the 40 paper facing is applied, and before the reverse side is painted or otherwise finished. This backing strengthens and protects the base; it may be of widely varying mesh and thickness of thread.

Having thus described my invention, I claim:

1. A flexible, waterproof covering of the character hereinbefore described, consisting essentially of a waterproofed rag felt base, 45 an unsaturated fabric fastened to one face thereof, and an overlay wearing surface upon said fabric.

2. A flexible, waterproof floor covering having a saturated, waterproofed felt base, 50 an unsaturated fabric plied to one face thereof, a priming or ground color coat applied on the face of the fabric, and an oil overlay wearing surface thereon.

3. A floor covering comprising a layer of 55 felt saturated or impregnated with pitch, a layer of unsaturated fabric plied upon one face of said felt layer, and an overlay wearing surface upon said fabric layer.

4. A base for sheet material of the oil 60 cloth or linoleum type comprising a layer of rag felt saturated or impregnated with pitch, and a layer of unsaturated paper plied upon one face of said felt layer by a coating of bituminous cement and forming 65 the overlay-receiving side of the base.

5. A base for sheet material of the oil cloth or linoleum type comprising a layer of felt saturated or impregnated with pitch, and a layer of unsaturated kraft paper plied 70 to said layer with pitch and forming the overlay-receiving side of the base.

In witness whereof I have hereunto signed my name at Maurer, New Jersey, this 1st day of July, 1919.

JOHN STROTHER MILLER, JR.
